UNITED STATES PATENT OFFICE.

JOHN H. STOOTS, OF KNOXVILLE, TENNESSEE.

ADJUSTABLE SPRING-SEAT.

1,319,976.

Specification of Letters Patent. Patented Oct. 28, 1919.

Application filed March 29, 1919. Serial No. 285,990.

To all whom it may concern:

Be it known that I, JOHN H. STOOTS, a citizen of the United States, residing at Knoxville, in the county of Knox and State 5 of Tennessee, have invented certain new and useful Improvements in Adjustable Spring-Seats, of which the following is a specification.

This invention relates to spring seats and 10 while specially designed for attachment to the cab of a locomotive for use by the engineer or fireman, may be employed with equally good results in many other relations where a seat of this general character is 15 required.

The object of the invention is to provide a spring seat of simple and durable construction capable of being adjusted both vertically and laterally with respect to its 20 support and which may be readily swung downwardly to inoperative position against said support when not in use so as to occupy very little space.

The invention further aims to provide an 25 adjustable spring seat including spaced tubular members or hangers having cushioning springs arranged therein and which serve to yieldably support a vertically movable rod on which is pivotally mounted a 30 removable seat, there being a supporting leg pivotally connected with the bottom of the seat and serving to yieldably support the forward end of said seat.

The invention further aims to provide 35 an auxiliary seat supporting rod or bracket adapted to be used in lieu of the main seat supporting rod in case the latter should become accidentally broken and from which auxiliary rod the seat may be conveniently 40 suspended when desired.

A still further object of the invention is generally to improve this class of devices so as to increase their utility, durability and efficiency.

45 In the accompanying drawings:

Figure 1 is a front elevation of an adjustable spring seat embodying the present invention, showing in dotted lines the seat suspended from the auxiliary supporting 50 rod;

Fig. 2 is a top plan view of Fig. 1;

Fig. 3 is a vertical sectional view showing in full lines the spring seat in operative position and in dotted lines said seat swung 55 downwardly to inoperative position against its support;

Fig. 4 is a detail perspective view of the seat detached;

Fig. 5 is a vertical sectional view of the front supporting leg showing the manner 60 of retaining the springs in position thereon;

Fig. 6 is a detail perspective view of one end of the seat supporting rod with the spacing elements or rings in position thereon.

Corresponding and like parts are referred to in the following description and indicated in all the views of the accompanying drawings by the same reference characters.

The improved device comprises spaced tubular hangers 5 closed at their lower ends and open at their upper ends, said hangers being each provided with an upstanding attaching ear 5' and oppositely disposed side 70 attaching ears 6 through which extend bolts or similar fastening devices 7 for the purpose of securing the hangers in position on a support indicated at 8. The inner faces of the tubular hangers 5 are provided with vertical slots 9 which open through the tops thereof with the lower ends of said slots preferably spaced a short distance above the closed ends of the hangers as best shown in Fig. 1 of the drawings. Arranged within 80 the hangers 5 are main and auxiliary cushioning springs 10 and 10' which serve to yieldably support a transverse seat carrying rod, indicated at 11. The rod 11 is preferably cylindrical in shape and is provided 85 at its opposite ends with reduced necks 12 which fit within the slots 9 and terminate in substantially flat circular heads 13 adapted to bear against the cushioning springs in the adjacent hangers.

Pivotally mounted for swinging movement on the supporting rod 11 is a seat 14 to the bottom of which are bolted or otherwise rigidly secured transverse cleats 15 the rear ends of which terminate in hooks 16 100 adapted to embrace the supporting rod 11 so as to permit the seat to be swung downwardly to inoperative position as indicated in dotted lines in Fig. 3 of the drawings. Secured to the bottom of the seat 14 is an 105 intermediate cleat 17 the forward end of which is provided with a depending eye 18 which receives a corresponding eye 19 formed on the adjacent end of a supporting leg 20. The supporting leg 20 is preferably in the 110 form of a threaded bolt and surrounding the threads on said bolt is a coiled spring 21

the lower end of which is adapted to bear against the floor and form a yieldable support for the front end of the seat. The spring 21 is retained in position on the leg 5 or bolt 20 by means of a substantially U-shaped clip 22 one end of which is provided with a slot for the reception of the bolt and is interposed between the adjacent coils or convolutions of the spring 21 and is bent 10 into engagement therewith, while the other end of the U-shaped clip is perforated to permit the passage of said bolt and is interposed between locking washers 23, as best shown in Fig. 5 of the drawings. If desired 15 an auxiliary spring 24 may be arranged within the main spring 21 and threaded on the lower end of the bolt 20. By rotating the nuts on the supporting leg or bolt 20 the main spring 21 may be supported 20 at any desired height on the leg 20.

Arranged within the tubular hangers 5 are one or more spacing members or disks 25, by removing or adding which the height of the supporting rod 11 may be varied at will. 25 Slidably mounted on the supporting rod 11 are a plurality of tubular members or rings 26 said rings being interposed between the hangers 5 and the sides of the adjacent cleats 15 so as to center the seat on the supporting rod. It is obvious that by shifting the rings 26 longitudinally on the rod 11 the seat 14 may be adjusted laterally with respect to the support 8.

It will thus be seen that the supporting 35 rod and cushioning springs 10 and 10' form a yieldable support for the rear end of the seat 14 while the leg 20 and spring 21 form a yieldable support for the forward end of said seat.

40 By swinging the supporting leg 20 laterally on its pivot 19 the seat may be folded downwardly and inwardly against the support 8 so as to occupy very little space when not in use.

45 Arranged above the seat 14 and detachably secured to the support 8 by screws or similar fastening devices 27, is an auxiliary seat supporting rod 28 from which the seat 14 may be suspended when desired as indicated by 50 dotted lines in Fig. 1 of the drawings. The auxiliary supporting rod 28 may also be used in lieu of the main supporting rod 11 should the latter become broken or otherwise impaired from constant use. Should 55 the rod 11 become broken the latter is removed through the open tops of the hangers 5 and the auxiliary rod 28 interposed between said hangers at the side attaching ears 6 and secured to the support 8 by the screws 60 27 and in which position the seat 14 may be pivotally connected therewith by passing the hooks 16 over the auxiliary rod, as will be readily understood.

65 The bottom of each hanger is preferably formed with an opening 29 and the heads 13

of the supporting rod are provided with similar openings 30 so as to permit the insertion of bolts for the purpose of holding down the seat supporting rod, if desired.

While the seat is particularly adapted for use in the cabs of locomotives and the like for convenience of the engineer or fireman, it will of course be understood that said seat may be employed with equally good results for any other purpose without departing 75 from the spirit of the invention.

Having thus described the invention, what is claimed as new is:

1. The combination with a support, of hangers secured to the support, cushioning members carried by the hangers, a supporting rod resting on the cushioning members, a seat pivotally mounted on the supporting rod and spacing members slidably mounted on the rod for centering the seat between 85 said hangers.

2. The combination with spaced hangers, cushioning members carried by the hangers, a supporting rod vertically adjustable with respect to the hangers and resting on the 90 cushioning members, a seat pivotally mounted for swinging movement on the supporting rod, spacing members slidably mounted on the rod for adjusting the seat laterally on said rod with respect to the hangers, and 95 means for yieldingly supporting the forward end of the seat.

3. The combination with spaced hangers having slots formed therein, main and auxiliary cushioning members carried by the 100 hangers, a supporting rod having reduced necks passing through the slots in the hangers and provided with enlarged heads resting on the cushioning members, a seat pivotally mounted on the supporting rod, 105 and a leg pivotally connected with the forward end of the seat and provided with a terminal cushioning spring for engagement with a support.

4. The combination with spaced tubular 110 hangers having their lower ends closed and their upper ends open, cushioning springs disposed within the hangers, spacing members interposed between the springs and the adjacent ends of the hangers, a supporting 115 rod resting on the cushioning springs, a removable seat pivotally mounted on the supporting rod, spacing sleeves slidably mounted on the rod for centering the seat between said hangers, and a leg pivotally connected 120 with the bottom of the seat near the forward end thereof.

5. The combination with spaced tubular hangers having their upper ends open and their lower ends closed and provided with 125 perforations, there being vertical slots formed in the inner faces of the hangers, main and auxiliary cushioning springs disposed within the tubular hangers, spacing members interposed between the cushioning 130

springs and the closed ends of the hangers, a supporting rod having terminal necks extending through the slots in the hangers and provided with enlarged heads resting on 5 the adjacent ends of the cushioning springs and formed with perforations registering with the perforations in the closed ends of the hangers, a seat provided with cleats having terminal hooks extending around the 10 supporting rod, and a supporting leg pivotally connected with the forward end of the seat.

6. The combination with spaced hangers, cushioning members carried by the hangers, 15 a supporting rod mounted for vertical movement between said hangers and resting on the cushioning springs, a removable seat pivotally mounted on the supporting rod, and spacing members slidably mounted on the 20 rod on opposite sides of the seat for centering the seat between said hangers.

7. The combination with spaced hangers, cushioning members carried by the hangers, a supporting rod connecting the hangers and 25 resting on the cushioning members, a seat pivotally mounted on the supporting rod and provided at its forward end with a depending eye, a leg pivotally connected with the eye, and provided with threads, a coiled 30 spring surrounding the leg, a substantially U-shaped clip having one end thereof fitting around the leg between certain of the con-

volutions of the spring and its other end provided with an opening for the reception of the leg, and clamping nuts engaging the 35 threads on said leg and bearing against the last mentioned end of the clip.

8. The combination with a support, of spaced tubular hangers having oppositely disposed attaching ears for engagement with 40 the support, the upper end of each hanger being open and the lower end thereof closed and there being a slot formed in the inner face of each hanger, cushioning springs arranged within the hangers, a rod connecting 45 said hangers and having its opposite ends provided with reduced necks extending through the slots of the hangers and terminating in enlarged heads resting on the cushioning springs, a folding seat pivotally 50 mounted on the rod, a forward leg pivotally connected with the bottom of the seat, a cushioning device carried by the lower end of the leg, spacing sleeves slidably mounted on the rod at opposite sides of the seat, and 55 other spacing members interposed between the lower ends of the cushioning springs and the closed ends of the hangers, said seat being foldable downwardly and rearwardly against the support when the forward leg 60 is swung laterally on its pivotal axis.

In testimony whereof I affix my signature.

JOHN H. STOOTS. [L. s.]
